UNITED STATES PATENT OFFICE.

JOHN A. MARQUETTE, OF HERSHY, NEBRASKA.

GRATE.

No. 910,078.

Specification of Letters Patent.

Patented Jan. 19, 1909.

Application filed April 2, 1908. Serial No. 424,840.

To all whom it may concern:

Be it known that I, JOHN A. MARQUETTE, citizen of the United States, residing at Hershey, in the county of Lincoln and State 5 of Nebraska, have invented certain new and useful Improvements in Grates, of which the following is a specification.

This invention contemplates certain new and useful improvements in grates of that 10 type designed particularly for use with ranges or the like, and the object of the invention is an improved device of this character, which may be readily operated to effectually discharge any ashes collecting 15 therein, and which may be accurately adjusted to fit the desired fire pot.

With this and other objects in view, that will more fully appear as the description proceeds, the invention consists in certain 20 constructions, arrangements and combinations of the parts that I shall hereinafter fully describe and then point out the novel features thereof in the appended claim.

For a full understanding of the invention 25 and the merits thereof, reference is to be had to the following description and accompanying drawing, in which:

Figure 1 is a top plan view of my improved grate; Fig. 2 is a transverse section 30 thereof; Fig. 3 is a detail view in section, of one of the rocking bars; and, Fig. 4 is a detail view in perspective, of a portion of one of the cross bars.

Corresponding and like parts are referred 35 to in the following description, and indicated in all the views of the drawing, by the same reference characters.

My improved grate embodies a plurality of longitudinally extending, transversely 40 spaced grate bars 1, the forward ends of which are upwardly disposed to form a front 2, the respective forward and rear extremities of the grate bars being bolted or otherwise rigidly secured to a front cross 45 bar 3, and a rear cross bar 4. The respective front and rear cross bars project upwardly and rearwardly beyond the extremities of the grate bars, as shown. The grate bars 1 are formed intermediate of their ends with 50 transversely alining and preferably circular openings 5 extending therethrough, and an actuating rod 6 that is preferably square in cross section is journaled in these openings 5 with its ends projecting outwardly beyond the grate bars 1. A plurality of rocking 55 bars 7 are mounted upon the actuating rod

6 between the spaced grate bars 1, and are formed with preferably square transverse openings 7a in which the actuating rod 6 fits, and is securely held so that the rocking 60 bars will turn therewith. These rocking bars are designed to be oscillated upon the operation of the actuating rod, so as to agitate the contents of the grate and effectually discharge any ashes or the like between the 65 spaced grate bars 1.

The front and rear cross bars 3 and 4 are formed at their ends with transversely extending spaced channels 8, and are also formed in their respective projecting portions with longitudinal spaced grooves 9, which permit a side or end section of the grate to be broken off along the line of one of these grooves or channels and to be readily detached from the grate, as may be required, to cause the latter to fit a desired fire pot. One of the projecting ends of the actuating rod 6 is preferably formed with a plurality of transversely extending spaced 70 marginal recesses 10, by means of which portions of the rod may be detached to adjust the latter in length.

After the grate has been fitted to the fire pot, it is mounted therein in the customary way, with the projecting ends of the actuating 85 rod journaled in the walls of the fire pot, and one of said ends extending through said wall, and being designed to be engaged by a crank handle or similar implement, so as to shake the grate.

It will be noted that in case the grate is not of sufficient width to fit the fire pot, one or more rocking bars 7 may be readily mounted upon the projecting ends of the actuating rod, to increase the width of the 95 grate.

From the above description, in connection with the accompanying drawing, it will be apparent that I have provided a simple, durable and efficient construction of grate, 100 which may be easily and cheaply manufactured, and which consists of comparatively few parts that may be readily assembled.

Having thus described the invention, what I claim is:

A grate of the character described, comprising a plurality of transversely spaced L-shaped grate bars forming the front and bottom of the grate, said grate bars being formed in the bottom with transversely alining 110 circular openings, cross bars secured to the corresponding extremities of the grate

bars and projecting therebeyond with their ends extending laterally beyond the respective extreme grate bars, said cross bars being formed in their projecting portions with 5 grooves extending longitudinally thereof and in their ends with transverse channels, an actuating rod square in cross section loosely mounted in the circular openings in the grate bars, and rocking bars positioned 10 between the spaced grate bars and formed with square openings in which the actuating

rod fits, said actuating rod having one of its ends projecting beyond the adjacent grate bar and being formed in said end with circumferential recesses, all as and for the purpose specified. 15

In testimony whereof I affix my signature in presence of two witnesses.

JOHN A. MARQUETTE. [L. S.]
